UNITED STATES PATENT OFFICE.

SETH WARD, OF PRINCETON, INDIANA.

BACK-BAND HOOK.

SPECIFICATION forming part of Letters Patent No. 337,215, dated March 2, 1886.

Application filed December 17, 1885. Serial No. 185,916. (No model.)

To all whom it may concern:

Be it known that I, SETH WARD, a citizen of the United States, residing at Princeton, in the county of Gibson and State of Indiana, 5 have invented certain new and useful Improvements in Back-Band Hooks, of which the following is a specification, reference being had therein to the accompanying drawings.

My improvement relates to back-band hooks 10 for harness, and is intended as an improvement on Patent No. 62,513, dated February 26, 1867, and issued to me.

The improvement in this case relates more 15 particularly to the shape and construction of the body of the hook and of the eyes formed therein, as will be hereinafter set forth.

In the accompanying drawings, making part 20 of this specification, Figure 1 represents a perspective of the hook secured to a section of back-band. Fig. 2 is a plan view. Fig. 3 represents a longitudinal section of the hook and a portion of the band, and Fig. 4 represents a cross-section of the hook and section of the band.

25 In the figures, A represents the body of the hook. One of the peculiarities is the raised or ridge back D.

In the patent to which I have referred, and 30 upon which this is an improvement, the main portion of the body and that which came in contact with the leather of the band was flat.

The difficulty I found with this flat body was this—moisture would collect beneath it, and remain and rot the leather. This I have ob- 35 viated by the present construction. From α to α' , it will be seen, that I leave in the body of the hook a narrow bearing-surface for the leather, which is punctured with holes for rivets to pass through. The body from this bearing- 40 surface is made hollow on the inner or under side, and rises, forming a ridge, D, which allows the body to stand away from the leather, and thus prevent moisture from collecting. The narrow space which is left for allowing 45 the hook to be confined to the leather allows moisture to escape, and thus prevents rot. This

construction is productive of a further advantage, which is clearly shown in Fig. 3. It allows the point C of the hook to be bent around and under the ridge in such manner that it 50 will more securely hold the trace.

I have used a modification in which, instead of forming a ridge on the back, I cut the metal away and form a skeleton body—an important feature in the construction of 55 this hook, which, while it may appear trivial, is of great importance in the actual use of the invention. This feature is the shape of the countersinks $a a a$ in the rim of the body, in which the rivet-heads press the leather when 60 the parts are being secured together. This countersink is made wide and slightly hollowing, but without any abrupt or sharp edges to cut the leather. The countersink is made shallow, so as to barely flush a flat thin-headed 65 rivet, F, which is slightly convex on its under side. The convexity of the rivet-head and the concavity of the countersinks conform to each other in shape, and the leather is never cut or split in confining it to the hook, all owing to 70 this peculiar construction. The ridge upon the back of the hook serves to give it strength without materially increasing its weight.

To compensate for the loss of metal by making a wide countersink, I have a small boss 75 thrown up on the opposite side, which gives the hook all necessary strength.

Having thus fully described my invention, what I claim as new, and desire to secure by Letters Patent, is—

As an article of manufacture, a back-band hook constructed of metal with a ridged back, a corresponding depression under said ridge, an upwardly and inwardly turned point, and countersunk flanged rivet-holes, all substan- 85 tially as specified.

In testimony whereof I affix my signature in presence of two witnesses.

SETH WARD.
